FUEL PRESSURE RESPONSIVE BURNER
CONTROL

Fred B. Aubert, Grosse Pointe, Mich.

Application January 15, 1944, Serial No. 518,331

11 Claims. (CL 158—28)

1

This invention relates to new and useful improvements in control systems for fluid fuel burners and more particularly for a liquid fuel or oil burner.

An object of the invention is to provide a system which is certain and positive in operation and which provides for scavenging of the combustion chamber.

Another object is to provide a control system in which, during the operating period, either ignition is on or flame is present at all times.

Another object is to provide electronic control means for instantaneous response to presence or absence of flame.

The foregoing and other objects will be noted in the following description.

The invention consists in the improved system or apparatus and the cooperative relation of the control devices comprising the same to be more fully described hereinafter and the novelty of which will be particularly pointed out and distinctly claimed.

In the accompanying drawings, to be taken as a part of this specification, there are fully and clearly illustrated several preferred embodiments of the invention, in which drawings

Figure 1 is a schematic view of a heating apparatus having a control system embodying the invention and showing the wiring diagram for the control devices, and

Fig. 2 is a detail view showing a portion of the diagram of Fig. 1 having added thereto a switch cut-out means for a warp switch heater.

Referring to the drawings by characters of reference, 1 designates generally a heating apparatus such as a boiler or furnace having a combustion chamber 2 and a water space or plenum chamber 3 for the medium to be heated. The apparatus 1 has a fluid fuel burner 4, preferably an oil burner, having an air supply conduit 5 discharging into the combustion chamber 2 and supplied with air under pressure by a blower or other air impelling means 6 driven by an electric motor 7. Liquid fuel or oil for mixture with the air is fed to the burner nozzle 8 which discharges into the chamber 2 concentric with the conduit 5. The nozzle 8 is connected to the feed line or supply conduit 9 which is supplied with oil under pressure by the pump 10 driven by gearing or other suitable means from the motor 7. The pump 10 preferably forms part of a pressure regulating device or unit 11 interposed between the pump discharge and the feed pipe 9. Intercalated in the pipe 9 between the pressure regulating device and the nozzle 8 there is a pres-

sure responsive switch 12 having normally open contacts including a fixed contact 13 and a pressure operated movable contact 14 engageable with the fixed contact. The fuel mixture discharged by the burner 4 may be ignited by ignition means 15 comprising a pair of spaced electrodes insulated from ground and connected by lead wires 16, 17 to the opposite ends of the secondary coil 18 of an ignition transformer 19 having one terminal of its primary coil 20 connected directly to one of the high voltage line or service wires 21 of the usual 110 v. A. C. supply and having its other terminal connected to a lead wire 22 connected to the other line or service wire 23, as will be hereinafter described.

Connected across the service line wires 21, 23 is the primary coil 24 of a transformer 25 having a plurality of secondary coils 26, 27 and 28, preferably of say 24 v., 6 v. and 142 v., respectively. The secondary coil 26 is connected to one terminal of a main control switch 29, such as a room thermostat, by a lead wire 30 having therein a normally closed pressure or temperature operated limit switch 31 responsive to the pressure or temperature of the medium in the boiler or furnace space 3. The switch 29, preferably positioned in the space or room of which the temperature is to be controlled and which is heated by the apparatus 1, has a compensating heater 32 which is energized when the switch 29 is closed by the bimetal actuator 33, as is well understood in the art. The fixed contact of the switch 29 is connected by a lead wire 34 to one terminal of the coil 35 of a main relay switch 36. The heater 32 has one terminal connected to the lead wire 34 and has its other terminal connected by a lead wire 37 leading to the other end terminal of the transformer secondary coil 26.

The relay 36 has a plurality of switches 38, 39 and 40 having movable contact carrying switch arms 41, 42 and 43 respectively which are movable in unison and which are preferably mechanically connected together to assure simultaneous operation. The switch 38 has its arm 42 connected to the line wire 23 and controls the burner motor 7, the primary coil of the ignition transformer 19, and the electric resistance heating element 44 of a burner motor controlling warp switch 45 comprising a safety timing means. The fixed contact 46 of the switch 39 is connected by a lead wire 47 to a switch arm 48 of an electron tube operated relay switch 49. The arm 48 forms part of a double throw switch 50 having a contact 51 normally closed or engaged by the cooperating contact of arm 48 and operable to control

the circuits of the burner motor, the ignition transformer, and the warp switch resistance coil. The switch 50 also has a contact 52 normally open or spaced from the contact of its cooperating arm 48 and operable to control the circuit of the burner motor. The relay switch 49 also includes a switch 53 having a movable contact carrying arm 54 cooperable with a fixed contact 55, the arm 54 being movable in unison with the arm 48, these arms preferably being mechanically connected together for simultaneous movement. The fixed contact 55 is connected by a lead wire 56 to the free or other end terminal of the main relay coil 35. The switch arm 54 is connected by lead wire 57 to the lead wire 37 and thence to the transformer secondary coil 26 so that the switch 53 controls the circuit of the main relay coil 35. The relay switch 40 has a fixed contact 59 and has its arm 43 connected by a lead wire 60 to the lead wire 56, the contact 59 being connected by a lead wire 60 to the lead wire 57 so that the switches 40 and 53 are in parallel with each other. The fixed contact 51 of the double throw switch 58 is connected by a lead wire 61 to one terminal of the resistance heater coil 44, which has its other terminal connected by a lead wire 62 to the service line wire 21. The ignition transformer primary lead wire 22 is connected to the lead wire 61 between the coil 44 and the switch contact 51 so that heater coil 44 and the transformer primary coil 20 are in shunt circuit. The lead wire 61 is connected by a lead wire 63 to a contact carrying switch arm 64 of a burner motor controlling switch 65 forming part of a motor safety relay switch 66. The switch 65 has its normally closed fixed contact 67 connected by a lead wire 68 to one terminal of the pump and blower motor 7 which has its other terminal connected by a lead wire 69 to the return line wire 21. The motor switch fixed contact 52 of tube relay 49 is connected by a lead wire 70 to the motor lead wire 68. The switch 38 of the main relay switch 36 has its fixed contact 71 connected by a lead wire 72 to the transformer secondary coil 26 at its connection to the room thermostat lead wire 30. The relay switch arm 41 cooperable with contact 71 is connected by a lead wire 73 to one terminal of the relay coil 74 of the motor safety relay switch 66, which has its other terminal connected by a lead wire 75 to the movable contact 14 of the pressure switch 12, from the fixed contact 13 of which a lead wire 76 is connected to the lead wire 57 and thence through lead wire 37 to the transformer secondary coil 26, so that the main relay switch 38 controls the relay coil 74. The motor safety relay switch 66 has a holding switch 77 with a fixed contact 78 connected by a lead wire 79 to the relay coil lead wire 75. The contact carrying switch arm 80 of switch 77 is movable in unison with the switch arm 64 and is preferably mechanically connected thereto so that arms 64 and 80 are simultaneously movable. The switch arm 80 of the normally open switch 77 is connected by a lead wire 81 to the lead wire 76 which is connected to the transformer secondary coil 26. The warp switch 45 is in parallel circuit with the holding switch 77 and has its fixed contact 82 connected by a lead wire 83 to the lead wire 81. The heat responsive or bimetal element 84 of the switch 45 carries a contact cooperable with contact 82 and is connected by a lead wire 85 to the pressure switch lead wire 75, so that each of the switches 77 and 45 is also in parallel circuit with the pressure switch 12, so that upon closure of any one of these parallel

connected switches, switches 29 and 38 having first been closed, the relay switch coil 74 will be energized.

The tube relay 49 has a relay coil 86 which forms part of an electrical network including an electron tube 87 controlling energization of the coil 86. The tube 87 has its anode 88 connected by a lead wire 89 to one terminal of the coil 86, which has its other terminal connected by a lead wire 90 to one terminal of the transformer secondary supply coil 28. From the other terminal of coil 28 which is connected to the coil 27 there extends, as from a coil intermediate tap, a lead wire 91 connected to the cathode 92 and connected to ground, as at 93. The cathode 92 is heated or energized by a filament 94 having one terminal connected by a lead wire 95 to the lead wire 81 and having its other terminal connected by a lead wire 96 to the free end of the transformer secondary coil 27. A screen grid 97 of tube 87 is connected through a resistor 98 and lead wire 99 to the cathode lead wire 81, the resistor 98 determining the negative bias on the grid 97. The tube control grid 100 is connected by a lead wire 101 to the cathode of a photo-electric cell or tube 102 responsive to burner flame and having its anode connected to ground as by a lead wire 103. The tube 102 is supported within and shielded from extraneous light by a box or casing 104 such that it responds only to the light rays of the burner flame in the combustion chamber 2. A tubular shield or light conducting member 105 opens at one end into the interior of the casing 104 in line with the tube 102 and has its other end extending into the combustion chamber 2 and sighted on the flame position. The negative bias on the control grid 100 is controlled in part by a pair of balancing condensers 106, 107, the condenser 106 having one side connected to a cathode lead wire 91 by a lead wire 108, and the other condenser having one side connected to the filament lead wire 96 by a lead wire 109. The condensers 106 and 107 have their other sides connected together and to the photo-cell lead wire 101 by a lead wire 110. Inserted in the photo-cell lead wire 101 between the grid 100 and the condenser lead wire 110, there is a resistor 111 which, together with the condensers 106 and 107, determines the negative bias on the control grid 100. The extent of negative drain at the photo-cell 102 necessary for the tube 87 to become sufficiently conducting to energize the relay coil 86 is therefore controlled by the negative bias on the screen grid 97 and on the control grid 100.

The operation of this control system is as follows: When the switch 29 is closed, as for example by a call for heat, and assuming that the line wires 21 and 23 are connected to a source of current supply, so that the transformer primary coil 24 is energized, current will flow from the transformer secondary coil 26 through lead wire 30 and the closed limit switch 31 to the bimetal blade 33 and through the closed switch 29 and lead wire 34 to the relay coil 35, from which current will flow through lead wire 56, the closed tube relay switch 53, lead wire 57 and lead wire 37 back to the transformer secondary coil 26. Energization of coil 35 will close the switch 38 preparatory to energizing the safety relay switch coil 74, will close the high voltage switch 39 to place in operation the timing means 45 and to energize the burner motor and ignition transformer and will close its holding switch 40. Accordingly current will flow from lead wire 58 through lead wire 59 to switch 40 and thence

via lead wire 60 to lead wire 57, so that the coil 38 will remain energized, even though switch 53 is opened. Closure of high voltage switch 39 will complete a circuit from line wire 23 to lead wire 47 which is connected to the double throw tube relay switch arm 48, thence through switch contact 51 and lead wire 61 to the warp switch heater coil 44 and thence via lead wire 62 to the line wire 21. The energized heater coil 44, upon the lapse of a predetermined time period, say two minutes, will have imparted sufficient heat to the warp switch blade or element 84 to close circuit between the blade contact and the fixed switch contact 82. Simultaneously with energization of the heater coil 44, current will flow from lead wire 61 through lead wire 22 to the ignition transformer coil 20 and thence to the return line wire 21, thus energizing the ignition transformer secondary coil 18 so that fuel igniting sparks will pass between the spark terminals of the ignition electrodes 15. Current from lead wire 61 will also flow through lead wire 63 to the switch arm 64 of the closed cut out switch 65 and thence via lead wire 68 to the motor 7 and back to the line wire 21 through lead wire 69. Ignition is therefore "on," simultaneously with energization of the burner motor 7 preparatory to the supply of a combustible mixture to the combustion chamber 2. Operation of motor 7 drives the fan 6 and the fuel pump 10, building up under the control of the pressure regulator 11 the desired spraying pressure at the nozzle 8. If for any reason the oil pressure in the conduit 9 does not build up to the desired spraying pressure sufficient to close the oil pressure responsive switch 12 prior to the lapse of the predetermined time period which will close the warp switch 45, then upon closure of switch 45 a circuit will be completed from the transformer secondary coil 26 through lead wire 72 to the now closed switch 38 and thence via lead wire 73 to the relay coil 74 and lead wires 75, 85 to the closed switch 45 and thence via lead wires 83, 81, 76, 57 and 37 back to the transformer secondary coil 26. Energization of relay coil 74 will break the motor circuit at switch 65 and will close its holding switch 77. The control system will thus be locked out and be maintained ineffective until the control switch or room thermostat 29 is opened and circuit is thus broken through the main relay coil 35 to permit switch 38 to open. After opening of the room thermostat switch 29 which deenergizes the heater coil 44, a period for scavenging of the combustion chamber 2 must elapse, which is predetermined by the time required for cooling of the bimetal element 84 sufficient to open the warp switch 45. Until the switch 45 opens at the end of the scavenging period, closure of the room thermostat 29 will energize the coil 74, thereby opening the motor switch 65 so that a recycling of the burner cannot be had. Assuming that the desired spraying pressure does build up in the conduit 9 so as to close switch 12 prior to closure of the timing means switch 45, then the relay coil 74 will be energized by current flow from the transformer secondary coil 26 through lead wire 72, closed relay switch 38, lead wire 73 to the relay coil 74, thence through lead wire 75 to and through the closed pressure switch contacts 14, 13 and lead wires 76, 57 and 37 back to the transformer secondary coil 26. At or upon the occurrence of the spraying pressure which will close switch contacts 13, 14, a combustible

75 mixture of air and oil should be discharging into the combustion chamber 2 to be instantly ignited by the ignition sparks. The occurrence of flame will render the photocell 102 conducting and cause the control grid 100 to become sufficiently positive for current flow through the electron tube 81, thereby energizing the tube relay coil 86. Accordingly, substantially simultaneously with the operation of the motor cut out relay switch 66 to deenergize the burner motor 7, the tube relay switch 49 will be energized, thereby remaking the motor circuit at the motor switch 50, so that the burner motor 7 will continue in operation. Although the lag between the opening of the motor switch 65 and the closure of the tube relay motor switch 50 is almost imperceptible in normal desired operation, it will be apparent that the inertia of the motor 7 will maintain oil pressure on the nozzle 8 sufficient to maintain the pressure switch 12 closed for an appreciable interval of say one or two seconds during which, if not instantly with flame, the switch 50 is closed to reenergize the burner motor 7. It may be noted that simultaneously with the opening of the motor cut out switch 65, the holding switch 77 was closed, so that coil 74 will be maintained energized to prevent restarting of the burner once the pressure switch 12 is closed, even though the pressure switch 12 might open for any reason prior to a loss of flame which would deenergize the tube relay coil 86. Upon closure by coil 86 of the tube relay double throw switch 50 at contact 52 to close the motor running circuit, the switch arm 48 breaks contact at 51, thereby deenergizing the warp switch heater coil 44 and the ignition transformer primary coil 20. The operation of the tube relay 49 also breaks the starting circuit for the coil 35 of the main relay 36 at the relay switch 63 so that if, for any reason the tube relay coil 86 is improperly energized as by a short circuit in the photocell circuit, or by the photocell 102 giving a false indication of flame, or if for any reason the switch arm 48 should remain in closed circuit running position with contact 52, the system could not be placed in operation.

With the oil burner placed in operation as above described, failure of flame for any reason will render the photocell 102 non-conducting, thereby instantly blocking current flow through the electron tube 81 which will deenergize the relay coil 86 so that double throw switch 50 will move to its starting position, as shown, breaking circuit at contact 52 and making circuit at contact 51. This will break the circuit of the burner motor 7, since relay switch 65 is open and will close the circuits through the ignition transformer primary coil 20 and through the warp switch heater coil 44. However, if flame is picked up by reason of the reenergization of the spark electrodes 15 before switch 45 closes or pressure switch 12 opens, the tube relay 49 will be reenergized and the burner will continue in operation. If the flame failure caused the system to shut down, then in order to restart the burner motor 7 after such a complete flame failure, the room thermostat switch 29 must be opened to deenergize the main relay coil 35 in order to break the circuit of the motor starting relay coil 74 to permit closure of switch 65. If the timing means switch 45 has closed due to the time elapsed following closure of switch 51 then the main relay switch 39 must be maintained

open long enough for the bimetal element 84 to cool and break circuit at contact 82, for otherwise closure of switch 29 will complete the circuit through the relay coil 74 via the switch 38 and the closed warp switch 45, thereby instantly breaking the starting motor circuit at switch 85. When the bimetal element 84 has cooled sufficiently due to deenergization of heater coil 44 to break circuit at contact 82, the circuit at the pressure switch 12 of course being open, the system can be restarted as above described upon closure of thermostat switch 29, as in response to call for heat. Should the pressure or temperature of the heat transfer medium in the heating apparatus space 3 exceed the desired safe limit at which switch 31 is opened, this opening of switch 31 will break the circuit through the main relay coil 35, thereby breaking the circuit to the burner motor at the main relay switch 39. Should the pressure or temperature drop sufficiently to close switch 31 while the switch 29 remains closed, then, switch 45 being open so that coil 74 is deenergized, the system will automatically again be placed in operation in the same manner as occurs upon closure of switch 29.

It may be noted that an electrode may be substituted for the photocell 102 and the light conducting tube 105, the electrode extending into proximity to the burner flame such that the electron tube 87 is controlled by capacitative impedance, such for example as is described in my co-pending application Serial No. 408,139, filed August 25, 1941, entitled "Burner control means."

Referring to Fig. 2 there is shown a changed circuit arrangement which serves to break the circuit of the heater coil 44 while maintaining the motor starting relay coil 74 energized subsequent to stoppage of the burner motor 7 due, as above described, to loss of flame or blocking of the electron tube 87. This may be accomplished by employing another relay switch 120 having a motor switch 121 positioned in and controlling current flow through the wire 47 and having a contact carrying switch arm 122 cooperable with a fixed contact 123. The switch 120 also has a holding switch 124 having a contact carrying switch arm 125 cooperable with a fixed contact 126 in parallel circuit with the warp switch 45. The switch arm 125 is connected by a lead wire 127 to the warp switch lead wire 85 and the switch contact 126 is connected by a lead wire 128 to the warp switch lead wire 83. The relay coil 129 of switch 120 is inserted in the lead wire 83 between its holding switch lead wire 128 and the lead wire 81. The switch arms 122 and 125 are movable in unison and are preferably mechanically connected together so as to assure simultaneous movement to break circuit at switch 121 and to make circuit at switch 124.

The operation of the circuit arrangement in Fig. 2 will, it is believed, be apparent from the foregoing and the description of Fig. 1 but it may be noted that upon flame failure which will deenergize relay coil 86 or in the event of initial failure of the electron tube 87 to become conducting, the heater coil 44 will cause the warp switch 45 to close, thereby completing a circuit through the relay coil 129 and also, if not theretofore completed, completing a circuit through the relay coil 74. Energization of coil 129 will attract or actuate the switch arm 122 to break circuit at switch 121 for the heater coil 44, the motor and the ignition transformer 19 and will

actuate arm 125 to make a holding circuit for itself at switch 124 and therefore the coil 44 and the bimetal element 84 will both cool to open the warp switch 45 preparatory to restarting the burner operating cycle by the manual opening and closing of the circuit of the main relay coil 35. It may be noted that the circuit of the relay coil 74 will remain completed as follows, from lead wire 85 through lead wire 127, to closed switch 124, and thence via lead wire 128 through the relay coil 129 to the lead wire 81, and accordingly the motor switch 85 will be held open, thereby doubly preventing starting of the burner motor 7. This feature of Fig. 2 not only eliminates consumption of current by the heater coil 44 during a lock out period but also eliminates the necessity of waiting for the coil 44 and element 84 to cool after the room thermostat switch 29 is opened, providing of course that the opening of the room thermostat switch 29 is had subsequent to the termination of the cooling period for element 84 initiated by opening of the switch 121 as above described.

What is claimed and is desired to be secured by Letters Patent of the United States is:

1. A heating apparatus comprising a fluid fuel burner, means to supply fuel under spraying pressure to said burner, starting and running circuits, 30 electrically operable means controlling said fuel supply means and energized from said circuits, means to ignite the fuel supplied to said burner, means including a closed switch in said starting circuit and controlling current flow to said operating means, electrically heated thermostatic timing means operable to open said switch, means responsive to fuel pressure and operable at fuel spraying pressure to open said closed switch, means operable upon opening of said switch to 40 maintain said switch open, means responsive to occurrence of flame at said burner, means including a switch in said running circuit and closed by said flame responsive means and controlling current flow to said electrically operable means, and main control means operable to control the supply of current to said switches and to said timing means.

2. A heating apparatus comprising a fluid fuel burner, a pump for supplying fuel to said burner, a motor starting circuit, a motor running circuit, a motor in said circuits and operable to drive said pump, means to ignite the fuel supplied to said burner, means including a switch in said motor starting circuit in series with said motor and normally in and urged to closed position, timing means operable to open said switch, means responsive to occurrence of flame at said burner, means including a switch positioned in said motor running circuit in series with said motor and closed by said responsive means, means including a relay switch means having a holding circuit for itself and operable to control the supply of current to said switches and to said timing means, means including a switch controlling energization of said relay switch means and opened by said flame responsive means, said relay switch means upon energization closing said holding circuit, and means including a main control switch operable to deenergize said holding circuit.

3. A heating apparatus comprising a liquid fuel burner, a pump for supplying fuel to said burner, a motor for driving said pump, means instantly responsive to flame at said burner, means including a switch controlling said motor and closed by 70 operation of said responsive means for energizing

said motor upon occurrence of flame, circuit means in shunt with said controlling switch and including a closed switch for starting said motor, means operable upon the occurrence of a fuel spraying pressure to open said closed switch, and safety timing means operable to open said closed switch.

4. A heating apparatus comprising a liquid fuel burner, a pump for supplying fuel to said burner, a motor for driving said pump, means instantly responsive to flame at said burner, means including a switch controlling said motor and closed by operation of said responsive means for energizing said motor upon occurrence of flame, circuit means in shunt with said controlling switch and including a closed switch for starting said motor, means operable upon the occurrence of a fuel spraying pressure to open said closed switch, electrically operable safety timing means operable to open said closed switch, and means operable by said flame responsive means to deenergize said timing means simultaneously with closure of said controlling switch.

5. A heating apparatus comprising a liquid fuel burner, a pump for supplying fuel to said burner, a motor for driving said pump, means instantly responsive to flame at said burner, means including a switch controlling said motor and closed by operation of said responsive means for energizing said motor upon occurrence of flame, circuit means in shunt with said controlling switch and including a closed switch for starting said motor, means operable upon the occurrence of a fuel spraying pressure to open said closed switch, safety timing means operable to open said closed switch, and means operable by said flame responsive means to stop operation of said timing means.

6. A heating apparatus comprising a liquid fuel burner, a pump for supplying fuel to said burner, a motor for driving said pump, means instantly responsive to flame at said burner, means including a switch controlling said motor and closed by operation of said responsive means for energizing said motor upon occurrence of flame, circuit means in shunt with said controlling switch and including a closed switch for starting said motor, means operable upon the occurrence of a fuel spraying pressure to open said closed switch, safety timing means operable to open said closed switch, means including a main switch cooperable with said closed switch and operable upon closure to start said motor, ignition means energized by closure of said main switch, and means operable by said timing means to deenergize said ignition means simultaneously with closure of said controlling switch.

7. A heating apparatus comprising a fluid fuel burner, a burner starting circuit, a pump for supplying fuel to said burner, a motor for driving said pump, means instantly responsive to the occurrence of flame at said burner, a holding circuit, a relay having its coil in said holding circuit and having a switch in said starting circuit and controlling current flow to said motor, said relay having a switch in and operable to close said holding circuit upon closure of said controlling switch, a closed safety switch in said starting circuit and opened by said flame responsive means upon occurrence of flame, a running circuit for said motor closed by said responsive means upon occurrence of flame.

8. A heating apparatus comprising a fluid fuel burner, electrically energizable means controlling the supply of fuel to said burner and having on

deenergization a time delay prior to stoppage of fuel supply to said burner, means instantly responsive to the occurrence of flame at said burner, a starting circuit and a holding circuit including a relay having a switch controlling current flow to said energizable means, said relay having a switch operable to close said holding circuit upon closure of said controlling switch, means including a closed switch in said starting circuit and opened by said flame responsive means upon occurrence of flame, means including a closed switch controlling current flow to said energizable means, means operable automatically substantially coincident with supply of fuel to said burner to open said last-named switch, and means including a switch for supplying current to said energizable means and closed by said flame responsive means simultaneously with the opening of said closed starting circuit switch.

9. A heating apparatus comprising a liquid fuel burner, a pump for supplying fuel under pressure to said burner, a motor for driving said pump, means including a switch responsive to the pressure of the fuel supplied by said pump, electric ignition means, means including a safety warp switch having a heating coil, energizing and holding circuits including a main relay having a switch controlling current flow to said motor, to said ignition means and to said heating coil, means including an electron tube relay having a switch in series with said main relay switch, a network including an electron tube rendered conducting to energize said tube relay to open said tube relay switch upon occurrence of flame at said burner, means including a switch closed upon opening of said tube relay switch and establishing a circuit for said motor, means including a switch closed by said main relay to close said holding circuit, a relay having a closed switch in series circuit with said first-named tube relay switch and energized to open its closed switch upon closure of said pressure responsive switch, means including said warp switch controlling the circuit of said last-named relay, means including a switch controlled by said main relay and controlling said last-named relay, said last-named relay having a holding circuit and having a switch operable to close its holding circuit, and means including a main control switch controlling the operation of said main relay.

10. A heating apparatus comprising a liquid fuel burner, a pump for supplying fuel under pressure to said burner, a circuit including a motor for driving said pump, a circuit including a switch responsive to the pressure of the fuel supplied by said pump, a circuit including electric ignition means, a circuit including a safety warp switch having a heating coil, a main relay having a switch controlling current flow to said circuits of said motor, said ignition means and said heating coil, an electron tube relay having a normally closed switch in series circuit with said main relay switch, a network having an electron tube rendered conducting to energize said tube relay to open said tube relay switch upon occurrence of flame at said burner, means including a switch closed upon opening of said tube relay switch and establishing a circuit for said motor, an energizing circuit and a holding circuit for the coil of said main relay, a closed switch in said energizing circuit and opened by and upon energization of said tube relay, a switch closed by said main relay and in and adapted to close said holding circuit, a relay having a closed switch in series circuit with said first-named tube relay switch and having

11

its coil in said warp switch circuit and in said parallel pressure switch circuit, said last-named relay opening its closed switch upon closure of said pressure responsive switch, a switch controlled by said main relay and controlling the parallel circuits of the coil of said last-named relay, a holding circuit for the coil of said last-named relay and having a switch operable to close its holding circuit, a main control switch controlling the operation of said main relay, and a 10 safety relay energized by closure of said warp switch and having a switch controlling the circuit to said heater coil, and a holding circuit for the coil of said safety relay and energized upon opening of its said heater coil switch.

11. A heating apparatus comprising a liquid fuel burner, a pump for supplying fuel to said burner, a motor for driving said pump, means instantly responsive to flame at said burner, means including a switch controlling said motor 20 and closed by operation of said responsive means

12

for energizing said motor upon occurrence of flame, circuit means in shunt with said controlling switch and including a closed switch for starting said motor, means operable upon the occurrence of a fuel spraying pressure to open said closed switch, and safety timing means operable to break the circuit through said circuit means.
